UNITED STATES PATENT OFFICE

FRANZ DEHLER, OF NEW YORK, N. Y.

PILE WIRE SPOON, HOLDER, FOR TWO EDGE CUTTING BLADES

Application filed April 11, 1932. Serial No. 604,487.

This invention relates to improvements in means for cutting the looped warp threads in pile fabrics such as mohairs, velvets, carpets and rugs, and it is the principal object 5 of my invention to provide a novel and improved cutting head or spoon for attachment to a pile wire and adapted to hold a blade with two cutting edges which I call universal duplex pile cutting wire with removable 10 blade, and which, while securely holding the blade will permit ready exchange and reversal of the same as soon as one of the cutting edges becomes dull.

One of the disadvantages connected with 15 the practical use of pile wires of the known constructions is the insecure hold of the cutting blades in the spoon so that during the rapid operation during which the pile wire is subjected to bending and torsional or other 20 stresses, they work quickly loose and enter the pile, doing great damage to the goods before this fact is discovered.

I positively avoid this disadvantage by 25 providing a spoon or cutting head which is equipped at its front part with a reinforcement serving the double purpose of strengthening the spoon and of holding the removable cutting blade at all times, and under all conditions in the proper cutting position positively preventing the blade from sliding out 30 through the top of the spoon.

Another object of my invention is the provision of the reinforcement in the front part 35 of the spoon with a shoulder or angular member engaging a suitably shaped recess in the head of the removable cutter blade.

Still another object of my invention is the provision of a blade holding or securing shoulder in the front part of the spoon serving 40 to cover part of the removable blade and also preventing the blade from falling out through the side of the spoon which frequently happens with the blades held in the spoon by a tongue laterally bent out of the material 45 of the spoon, and has the further purpose of strengthening the entire spoon construction.

A further object of my invention is the provision of a spoon for holding a double edged cutter blade provided with a groove so 50 constructed as to allow a ready insertion of

the blade into the groove but having the lower edge of the material forming the groove curved in such manner as to prevent the loose cutting edge of the blade to touch the bottom of the groove and becoming dulled. 55

A still further object of my invention is the provision of a novel and improved cutter blade for the spoons of pile wires provided with two curved cutting edges for allowing the cutting of the loops with a certain swing 60 greatly prolonging the period of usefulness of the blade. It will, however, be evident, that I may construct my cutter blade with one curved and one straight edge if so desired or required during the practical use of the same. 65 It will be clear that I may construct my spoon for pile wires so as to fit all the various types of pile wires used in the various types of looms accommodating the same to the various types of blades used. 70

These and other objects and advantages of my invention will become more fully known as the description thereof proceeds and will then be specifically defined in the appended 75 claims.

In the accompanying drawing forming a material part of this disclosure:

Fig. 1 is a side elevation of a spoon constructed according to my invention, partly 80 in section.

Fig. 2 is a top edge view of the same.

Fig. 3 illustrates the formation of the walls forming the spoon groove.

Fig. 4 shows detail views of cutter blades 85 constructed according to my invention.

As illustrated, a spoon 10 having a slotted or slotted stem adapted to be secured to a pile wire of any suitable construction, has near its front part a reinforcement 11 formed integrally with the inner rear wall of the spoon and transversely thereto, said reinforcement is equipped with an inwardly directed shoulder 12 adapted to engage into a recess at the head of a cutter blade as will hereafter be more fully described. 90

A blade securing shoulder 13 or side-support is formed with the spoon and is adapted to cover part of the blade 14 when the same is inserted into the spoon through the groove 15 of the spoon, and to prevent the blade 100

from falling and working out of the spoon and acts also as a strengthening means for the entire spoon.

The formation of the walls 16 or slot 5 groove 15 is best shown in Figure 3 in which the swaged walls of the blade receiving groove are shown to have their lower edges on a curve 17 to prevent damage to the lower cutting edge of the blade resting in the 10 groove.

The cutting blades are shown in Figure 4, in which 18 shows a blade having an upper cutting edge 19 and a lower cutting edge 20. The head 21 of the blade is recessed as at 22 15 for engagement by the shoulder 12 of the reinforcement 11 of the spoon. Both cutting edges are curved to arrange for a cut with a certain swing on the arc of a circle to increase the period of usefulness for the blade. The 20 blade 23 also shown in Figure 4 has a curved upper edge 24 and a straight lower cutting edge 25.

In operation, the blade is inserted into groove 15 from the top in the usual manner 25 through a slot in the upper edge of the spoon and its recess is engaged with the shoulder in the reinforcement, the blade will then be securely held between the rear wall of the spoon and the blade securing shoulder 13 of the 30 spoon, and cannot fall out during the operation of the pile cutter. If the upper cutting edge of the blade becomes dull the blade is simply removed from the groove through the slot in the spoon and reversed 35 and placed again into the spoon so as to present a new cutting edge to the pile.

The curved lower edge of the swaged walls from the cutter groove will protect the lower curved and unused cutting edge during the 40 cutting operation performed by the upper edge against damage by the grooved bottom or edges of the swaged walls.

It will be understood that I have described and shown the preferred form of my device 45 as one example only of the many possible ways to practically construct the same, and that I may make such changes in the general arrangement of the spoon and the blades to be used therewith as come within the scope 50 of the appended claims, without departure from the spirit of my invention and the principles involved.

Having thus described my invention what I claim as new and desire to secure by Letters Patent is:

1. A spoon or holder for the cutters of pile wires comprising a slotted stem adapted to be attached to a pile wire, a means formed with said spoon to securely hold a double-edged blade inserted into the spoon through the slotted stem thereof and pushed forward, a plate integral with said spoon cut away so

as not to bear on the cutting edge of the blade to hold the blade in place and protecting the lower unused edge of the cutter blade in said spoon against damage.

2. A spoon or holder for the pile cutters 70 of looms having a blade receiving groove, comprising a body, a slotted stem, a reinforcement on said body having a shoulder formed therewith adapted to engage a recessed, double-edged cutter blade, and a wall 75 integral with said body cut away so as not to bear on the cutting edge of the blade inserted through the slot in said stem for protecting the unused lower edge of said cutter blade in said spoon.

3. A holder for the pile cutters in looms having a blade receiving groove, comprising a substantially spoon-shaped body, a slotted stem therefor adapted to be attached to a pile wire, a reinforcement transversely 85 formed with said body wall near the outer edge of the spoon, a shoulder formed at the inner edge of said reinforcement, a double-edged cutter blade having a recess for engagement by said shoulder and inserted into 90 the spoon through the slotted stem thereof, a cover parallel to said body wall and integral therewith, said spoon spaced therefrom, said cover holding the blade in place and cut away so as not to bear on the cutting edge of 95 said blade and to protect the inner lower edge of the blade in said spoon.

4. A spoon or holder for the cutters of pile wires, comprising a slotted stem, a spoon-shaped wall formed therewith, a transverse 100 abutment formed with said wall near the outer end thereof, a shoulder formed at the inner edge of said abutments, adapted to engage a recess of a cutter blade inserted into 105 said spoon through the slotted stem and pushed forward into engagement with said shoulder, a wall formed integrally with said spoon to cover part of the cutter blade and swaged inner walls forming a groove at the cutter end having curved lower edges to protect the lower edge of said curve in its position in said groove.

5. The combination of a spoon for the pile wires of looms having a shouldered reinforcement and a holder blade with a cutter blade 115 having a recessed head adapted to be engaged by the shoulder of said spoon reinforcement, a means integral with the spoon extending to part of the outer blade to hold the same exchangeably in the spoon, and 120 swaged walls in said spoon forming a groove in said spoon to protect the lower edge of the cutter blade.

Signed at New York, in the county of New York, and State of New York, this 6th day of April A. D. 1932.

FRANZ DEHLER.
